CLAIM

We claim the ornamental design for a vibrating ring, as shown and described.

DESCRIPTION

FIG. 1 is a front, top, right side perspective view of our vibrating ring device, showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a top side, elevational view thereof; and,

FIG. 7 is a bottom side, elevational view thereof.
